UNITED STATES PATENT OFFICE.

MICHAEL AHEARN, OF DENVER, COLORADO.

STONE-CUTTING MACHINE.

1,137,731.

Specification of Letters Patent.

Patented May 4, 1915.

Application filed June 5, 1914. Serial No. 843,271.

To all whom it may concern:

Be it known that I, MICHAEL AHEARN, a citizen of the United States, residing at Denver, in the county of Denver and State of Colorado, have invented a new and useful Stone-Cutting Machine, of which the following is a specification.

The present invention appertains to stone cutting apparatus, and aims to provide a 10 novel and improved machine for cutting blocks of stone, marble or the like, into slabs.

The present invention contemplates the provision of a stone cutting apparatus embodying a unique assemblage of its component parts, and which is improved generally in its construction, to enhance the utility thereof.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed, can be made within the scope of what is claimed, without departing from the spirit of the invention.

The invention has been illustrated in its 30 preferred embodiment in the accompanying drawing, wherein:

Figure 1 is an end view of the apparatus. Fig. 2 is a sectional view taken on the line 2—2 of Fig. 1. Fig. 3 is a fragmental detail 35 in perspective of the band saw. Fig. 4 is a sectional detail taken on the line 4—4 of Fig. 2.

The present apparatus embodies a base frame 1 having an upper table 2, upon 40 which is disposed a pair of flat carriages 3. The carriages 3 are disposed side by side at the opposite sides of the longitudinal median line of the table 2, and are provided with longitudinal depending ribs 4 slidably 45 engaging in longitudinal grooves or channels 5 provided in the upper surface or face of the table 2, to constrain the carriages for longitudinal sliding or reciprocatory movements from one end of the frame 1 or its 50 table 2, to the other.

In order that the carriages 3 may be moved longitudinally, a longitudinal screw 6 is disposed below each of the carriages 3, and has its terminal portions journaled

through bearings 7 formed upon the ends 55 of the frame 1 adjacent the table 2, the carriages 3 having depending nut portions 8 embracing and threadedly engaging the screws 6 and working within longitudinal slots 9 provided in the table. Thus, when 60 the screws 6 are rotated, the carriages 3 may be reciprocated or moved upon the table.

A longitudinal actuating shaft 10 is journaled through the frame 1 below the table 2, and midway between the sides 65 thereof, and a pulley wheel 11 is keyed or secured upon the inner end of the actuating shaft 10 midway between the ends of the frame 1. An upper pulley wheel 12 is disposed above the lower pulley wheel 11, the 70 lower pulley wheel being disposed completely below the table 2, and the pulley wheel 12 being supported as will presently appear. A pair of standards or uprights 13 are attached to the sides of the frame 1, and 75 have their upper ends connected by a lintel or cross beam 14. The lintel or beam 14 is provided intermediate its ends with a vertical opening 15 forming a guide or slideway and having a bearing or yoke portion 80 16 connecting the lower end portions of the sides of the guide or slideway 15. A vertically movable slide 17 is mounted between the sides or rails of the guide 15, above the yoke or bearing 16, and a U-shaped bracket 85 18 has one arm attached integrally to one side of the slide 17 and the upper ends of the arms of the bracket 18 are provided with bearings 19 between which the pulley wheel 12 is trunnioned or journaled. The lower 90 portion of the pulley wheel 12 works through the bracket 18.

In order to adjust the slide 17 vertically, an adjusting screw 20 is journaled through the bearing or yoke 16, and is constrained 95 against vertical or longitudinal movement therethrough, a hand wheel 21 being secured upon the lower end of the screw 20, while that side of the slide 17 remote from the bracket 18 is provided with a 100 projecting nut portion 22 threadedly engaging over the screw 20. Thus, when the screw 20 is rotated through the medium of the hand wheel 21, the slide 17 will be adjusted either upwardly or downwardly, as 105 desired.

The band saw or endless cutter 23 is trained over the lower and upper pulley wheels 11

and 12, respectively, to provide two vertical runs coöperating with the respective carriages 3. The vertical runs of the band saw or endless cutter 23 pass through suitable openings or slots in the table 2, and through longitudinal slots 23^a provided in the carriages 3. Thus, the band saw or cutter passes through the carriages, but the carriages are free to move longitudinally with 10 out any interference between the band saw and carriages. The detail construction of the band saw 23 will be described hereinafter.

As a means for actuating the carriages 3, or the feed screws 6 thereof, a pair of gear wheels 24 are journaled to one end of the frame 1, and intermesh with a pinion 25 keyed or secured upon the actuating shaft 10. The gear wheels 24 are provided 20 upon their outer faces with diametrical channels or guides 26 within which are adjustably mounted the wrist pins 27, whereby the wrist pins may be adjusted at the desired radii with respect to the centers of the gear 25 wheels 24. A pair of links 28 have certain of their ends connected to the wrist pins 27, and have their outer ends connected to levers 29 which are fulcrumed upon the corresponding end portions of the screws 6. 30 Pawls or dogs 30 are carried by the levers 29 and engage ratchet wheels 31 keyed or secured upon the screws 6 adjacent the levers 29. It is also preferable to provide hand wheels 32 upon the extremities of the 35 screws 6, outside of the ratchet wheels 31, in order that the screws may be manually rotated when desired.

Coming to the detail construction of the band saw or endless cutter, the same is provided along one edge, with a series of dove-tailed recesses 33 in which are snugly fitted dove-tailed inserts 34, and rivets or securing members 35 are engaged between the beveled or inclined ends of the dove-tailed 45 recesses 33 and the inserts 34, to lock the inserts in place. The inserts 34 are equipped with inset cutting elements 36, which may be of hardened steel, diamond, bort, or the like. That edge of the band 50 saw 23 which is provided with the inserts 34, is provided with notches 37 intermediate the recesses 33, to enable the band saw to flex readily as it passes over the pulley wheels 11 and 12. The notches or slots 37 55 also assist in carrying the pulverized stone from the kerfs or slots cut in the blocks of stone, as will be obvious.

In operation, the carriages 3 are first set at that end of the frame 1 remote from the 60 ratchet wheels 31, inasmuch as the cutting edges of the band saw 23 project toward the said end. The blocks of stone, marble, or the like, 38, are then placed or seated upon the carriages 3, and are moved to the proper 65 positions with respect to the vertical runs

of the band saw. Then, as the shaft 10 is driven by a prime mover or suitable source of power, the lower pulley wheel 11 will be rotated to actuate the band saw. The vertical runs of the band saw are then moved 70 upwardly and downwardly, respectively, through the slots 23^a of the carriages 3, it being possible to render the runs of the band saw taut, by sliding the slide 17 vertically through the medium of the adjusting screw 75 20. Now, as the shaft 10 rotates to actuate the band saw, the gear wheels 24 will be rotated, and the wrist pins 27 will then reciprocate the links 28 to oscillate the levers 29. The levers 29 being oscillated will 80 cause the pawls or dogs 30 to engage the ratchet wheels 31 for properly rotating the feed screws 6 to move the carriages 3 with a slow intermittent or step by step movement from one end of the table 2 to the 85 other. Thus, the vertical runs of the band saw will cut slabs 39 from the blocks of stone, marble, or the like, 38, when the carriages 3 have been moved sufficiently to the respective end of the frame. Then, by 90 releasing the pawls or dogs 30, the screws 6 may be rotated in a reverse direction, by means of the hand wheels 32, to return the carriages 3 to normal or initial position for a repeated operation, the blocks 38 being 95 reset upon the carriages as will be apparent. The operation may thus be repeated until the blocks 38 have been completely sawed or cut into slabs of any desired thickness. The velocity of the carriages 3 may 100 be adjusted, by adjusting the wrist pins 27 within the guides or channels 26 of the gear wheels 24, to regulate the throw of the links 28 which actuate the levers 29. The inset cutting elements 36 of the band 105 saw will serve to cut or saw the kerfs in the blocks of stone, marble, or the like, it being preferable to pour water or other cooling and cleansing agent into the kerfs or cuts made by the band saw. The pulverized stone may thus be washed out by the water, assisted by the notches or slots 37 which will catch the pulverized stone to carry it outwardly.

From the foregoing, taken in connection 115 with the drawing, the advantages and attributes of the present apparatus will be obvious to those versed in the art, without further comment being necessary.

Having thus described the invention, 120 what is claimed as new is:—

In an apparatus of the character described, a frame, a pair of carriages disposed side by side and slidably longitudinally upon the frame, a pair of feed screws 125 carried by the frame below the respective carriages, the carriages having nut portions engaging the respective feed screws, a driving shaft carried by the frame below the carriages, adjustable means operatively con- 130

necting the driving shaft and the said feed screws, a pulley wheel carried by the said driving shaft below the carriages, an upper adjustably mounted pulley, and a band saw 5 trained around the said pulley wheels, the carriages having longitudinal slots through which the runs of the band saw pass.

In testimony that I claim the foregoing as my own, I have hereto affixed my signature in the presence of two witnesses.

MICHAEL AHEARN.
